UNITED STATES PATENT OFFICE.

EDWARD A. STIGGINS, OF BEVERLY, MASSACHUSETTS, ASSIGNOR TO UNITED SHOE MACHINERY COMPANY, OF PATERSON, NEW JERSEY, A CORPORATION OF NEW JERSEY.

PUNCHING-MACHINE.

1,163,116.

Specification of Letters Patent.

Patented Dec. 7, 1915.

Application filed August 9, 1911. Serial No. 643,176.

To all whom it may concern:

Be it known that I, EDWARD A. STIGGINS, a citizen of the United States, residing at Beverly, in the county of Essex and State 5 of Massachusetts, have invented certain Improvements in Punching-Machines, of which the following description, in connection with the accompanying drawings, is a specification, like reference characters on the 10 drawings indicating like parts in the several figures.

This invention relates to punching machines and is herein illustrated as embodied in a machine for forming ornamental perforations or indentations in pieces of stock which are to be used in the manufacture of 15 boots and shoes.

The illustrative punching machine is shown as provided with that type of 20 punches which produce perforations in the stock, and in order to promote brevity the term "perforations" will be employed to designate the characters indented or cut by the punches; but it should be understood 25 that punches of any desired type may be used.

These ornamental perforations are usually located in lines which follow the contours of the edges of the upper of a shoe, and inasmuch as these contours consist in part of 30 curves it is necessary either to produce the perforations one at a time or to produce the whole line at a single operation. The latter method is impractical for general use since the contours of the uppers of shoes vary 35 greatly, and the first method is therefore the one commonly used. As has been stated, these lines of perforations are for the purpose of ornamentation, and it is consequently 40 desirable that provision be made for varying the character and sequence of the individual perforations with a view to varying the finished design.

The general object of the present invention is, therefore, the production of lines of ornamental perforations which consist of recurring groups, the individuality of the groups being determined by the character and sequence of the perforations which form 45 them.

To this end one feature of the invention consists in the combination in a machine of the class described of a plurality of punches, means for forcing said punches into the

stock, and means for causing said punches to 55 act in a predetermined sequence. And in the illustrative machine the punches are mounted in a turret which is carried by a reciprocating punch-bar, and means are provided for moving said turret angularly 60 in timed relation with the reciprocation of said bar.

Where the line of perforations to be produced is to be straight or approximately so, it would be possible to mount upon the reciprocating punch-bar of an ordinary machine a small group of punches arranged in line, in which case the resulting line of perforations would consist of recurring groups 65 each group consisting of a number of perforations equal to the number of punches. It is desirable, however, to be able to increase the size of the recurring groups without increasing the number of punches employed, and a further feature of this invention consists in the provision of a given 70 number of punches each formed to produce a perforation of a particular character and means for actuating said punches to produce a line of perforations made up of recurring groups, each group containing a greater 75 number of perforations than the number of punches. And in the illustrative machine this is accomplished by oscillating the turret referred to above so that one of 80 the punches is caused to operate oftener than another.

These and other features of the invention including certain details of construction and combinations of parts will be described in 90 connection with an illustrative machine and pointed out in the appended claims.

Referring now to the accompanying drawings:—Figure 1 is a side elevation of a machine in which the present invention is embodied; Fig. 2 is an end elevation of a portion of the machine; Fig. 3 is an elevation showing the lower end of the punch-bar together with the holder and the punches; Fig. 4 is a detail showing the turret in which 95 the punches are mounted; Fig. 5 is an elevation of the turret; and Fig. 6 is a detail perspective showing a piece of leather which 100 has been operated upon by the machine.

The invention is illustrated in connection 105 with the punching machine shown and described in U. S. patent to Flynt, No. 941,704, dated Nov. 30, 1909.

Referring more particularly to Fig. 1, the driving shaft 1, mounted in bearings in the frame 3, carries a driving pulley 5 which may be connected with said shaft by 5 clutch mechanism indicated comprehensively by 7. The punch-bar 9 is slidably mounted in the punch-bar carrier 11, said punch-bar being reciprocated in one direction by a cam on the shaft 1 and in the opposite 10 direction by a spring held in the punch-bar carrier. The punch-bar carrier is movable in a small arc about the axis of the driving shaft in the direction of the line of feed, said carrier being actuated by cams on 15 the shaft 1 which coöperate with rollers 13 carried by a lever 15 which is pivoted to the punch-bar carrier at 17 and is acted upon near its central portion by a fulcrum block 18 carried at the inner end of a clamping 20 screw 19, this screw being adjustable in a slot 21 in the frame of the machine to vary the throw of the punch-bar carrier and thereby the extent of feed of the stock. A presser foot 23 is intermittently raised and 25 lowered at the proper time to permit the punch to feed the stock, and an edge gage 25 for guiding the work is adjustably clamped to the frame of the machine.

The machine will not be described further 30 in detail other than to say that its operation is briefly as follows: Starting with the parts as shown in Fig. 1, the punch-bar is forced downwardly to cause the punch to enter the stock; the punch-bar carrier is then swung 35 forwardly in the line of feed to cause the punch to feed the stock; the punch-bar is raised and the punch-bar carrier swung back to the position shown. The machine, in short, is of the general type known as 40 feeding and punching machines in which the punch, besides being reciprocated, is moved laterally to feed the stock, and the details of the particular machine shown are clearly set forth in the patent referred to 45 above. It should be understood, however, that the invention is not limited to this particular machine but may be employed in connection with machines of other types.

Referring now more particularly to the 50 remaining figures, a holder 27 fastened to the punch-bar 9 by means of a pinch screw 29 has formed therein a socket to receive a turret 31. This turret (best shown in Figs. 4 and 5) has a cylindrical portion provided with two sets of teeth, one set 33 serving merely as guides for the proper positioning of the turret when it is placed in the holder and the other set 35 serving as a mutilated pinion by means of which the 55 turret may be properly actuated. The punches herein shown as a square tube 37, two small tubes 39 and a cylindrical tube 41 are driven into the turret and bear with their rear ends against a ring 43, said ring 60 having perforations to permit the escape 65

of the waste material cut out by the punches.

In the illustrated machine the turret is oscillated, and in order to produce this oscillation a rack 45 which meshes with the teeth 35 is slidable in a guideway 47 in the holder, said rack being formed at its outer end with a vertical guideway in which a block 49, pivoted to an actuating lever 51, is slidable. This lever 51, which is pivoted 75 to the punch-bar carrier at 53, is provided at its upper end with a cam roll 55 which travels in a cam track 57 formed in a large gear 59, said gear being rotatably mounted on a stud 60 held by the punch-bar carrier 80 and consequently movable with said carrier. A gear 61 fast to the driving shaft 1 actuates the gear 59 and thereby, through the cam track 57, the roll 55, the lever 51, and the rack 45, actuates the turret 31. 85

In order to permit ready removal and replacement of the turret 31, said turret is held in place by a latch 63 pivoted to the holder 27 at 65 and provided with a semi-cylindrical projection 67 arranged to enter 90 the bore of the turret, said latch being provided with a rotatable locking member 69 having at its inner end a locking pin 71 which enters a recess in one wall of the guideway 47. 95

The teeth 33, as has been explained, are for the purpose of insuring that the turret shall be properly placed in the machine and their location is such that it is impossible to slide the turret into place except in one 100 position, it being necessary for these teeth to be slid past those of the rack 45.

In order to insure that the material being operated upon shall be properly held down upon the table 73 during the punching operation, as well as during the time that the punches are being withdrawn, a stripper 75 is carried by an upright member 77 slidably mounted in a guideway in the holder 27 and normally held in lowered position, as 105 shown in Fig. 2, by a grasshopper spring 78, one end of said spring being coiled about the head of a screw 79 which is threaded into the member 77 and the other end of the spring being coiled about the head of a 110 screw 81 which passes through a slot 83 in the member 77 and is threaded into the holder 27. 115

The operation of the machine is as follows: Starting with the machine in the position shown in Fig. 2, the punch-bar 9 is forced downwardly thereby forcing the stripper 75 against the stock and forcing the punch 39 into the stock; the punch-bar carrier 11 is then swung to the left to feed 120 the stock. During this movement of the carrier the gear 59 has been rotating in the direction indicated by the arrow, but owing to the shape of the camway 57, the cam roll 55 has not been moved with respect to the 125

center of the gear 59. The punch-bar is raised to disengage the punch from the stock and the punch-bar carrier is swung back into the position shown. In the meantime, 5 the roller 55 has been moved to the left thereby moving the rack 45 to the right and bringing the punch 41 into operative position. The movements of the punch-bar and the punch described above are now repeated 10 after which the punch 39 is again brought into operative position. Similarly the punch 37 is next brought into operative position. In this way the punch 39 is caused to operate upon the stock once for every operation of either of the other punches, and the resulting pattern appears as shown in Fig. 6. Referring now to this figure, it will be seen that the line of perforations which results from the operation of the machine is 15 made up of recurring groups of four perforations, one of which is duplicated in each group. If four punches had been employed the resulting line of perforations would have been made up of recurring groups of 20 six, two of which would have been duplicated in each group. In short, where more than two punches are used and the turret is 25 oscillated, the number of perforations in the recurring groups which make up the finished line will always be greater than the 30 number of punches.

It should be noted particularly that the punches in the present machine are operated one at a time and that, by reason of this mode 35 of operation, a line of perforations of varied characters may be formed along the curved edge of the piece of stock, or a curved line of such perforations may be located as desired upon said piece.

Although the invention has been set forth 40 in connection with a machine for forming perforations in stock, it should be understood that the invention is not limited in the scope of its application to the particular 45 machine shown and described.

Having fully described my invention, what I claim as new and desire to secure by Letters Patent of the United States is:—

1. A machine of the class described having 50 a punch bar, means for reciprocating said punch bar, a punch bar carrier, and means for moving said carrier laterally in combination with a plurality of punches carried by said punch bar, and automatic means for causing said punches to be brought into operative position in a predetermined sequence.

2. A machine of the class described having 55 a punch bar, means for reciprocating said punch bar, a punch bar carrier, and means for moving said carrier laterally in combination with a plurality of punches carried by said punch bar, and automatic means for moving said punches with respect to said bar.

3. A machine of the class described having 60 a punch bar, means for reciprocating said punch bar, a punch bar carrier, and means for moving said carrier laterally in combination with a plurality of punches carried by said punch bar, and automatic means for oscillating said punches.

4. A machine of the class described having 65 a punch bar, means for reciprocating said punch bar, a punch bar carrier, and means for moving said carrier laterally in combination with a plurality of punches carried by said punch bar, and automatic means for moving said punches angularly in timed relation to the reciprocation and 70 lateral movements of said bar.

5. A machine of the class described having 75 a punch bar, means for reciprocating said punch bar, a punch bar carrier, and means for moving said carrier laterally in combination with a holder movable with 80 said punch bar, a stripper yieldingly mounted in said holder, a turret angularly movable in said holder, and means for moving said turret in timed relation to the reciprocation and lateral movement of said punch bar.

6. A machine of the class described having 85 a punch bar, means for reciprocating said punch bar, a punch bar carrier, and means for moving said carrier laterally in combination with a holder movable with 90 said punch bar, a stripper yieldingly mounted in said holder, a turret angularly movable in said holder, and means mounted upon said punch bar carrier for imparting 95 intermittent movement to said turret.

7. A machine of the class described having, in combination, a supporting table over 100 which the stock is fed, a punch bar, means for reciprocating said punch bar, a given number of punches carried by said bar each punch formed to produce a particular character, and means for actuating the punches in timed relation to the reciprocation of the 105 bar to produce a line of characters made up of recurring groups, each group containing a greater number of characters than the 110 number of punches.

8. A machine of the class described having, in combination, a punch bar, means for reciprocating said bar, a holder fast to said bar and provided with a cylindrical socket, a turret adapted to be held in said socket, and a rack for operating said turret, there 120 being formed upon said turret a set of guiding teeth to insure its proper placing, and a set of operating teeth to coact with said rack.

9. A machine of the class described having 125 a punch-bar, means for reciprocating said punch-bar, a punch-bar carrier and means for moving said carrier laterally, in combination with a cam mounted upon said laterally movable carrier, an angularly mov- 130

able turret mounted upon said punch-bar, punches carried by said turret, and means for actuating said turret from said cam.

10. A machine of the class described having, in combination, a plurality of punches arranged to operate one at a time and means for causing one of said punches to operate oftener than another.

11. A machine of the class described having, in combination, a given number of punches each formed to produce a particular character, and means for actuating said punches to produce a line of characters made up of recurring groups, each group containing a greater number of characters than the number of punches.

12. A machine of the class described having, in combination, a bed for supporting a piece of stock, a punch bar, means for reciprocating said bar, three punches carried by said bar and arranged to be operated one at a time, each punch being movable with respect to said bar into and out of operative position, and automatic means for causing one of said punches to be moved into said position twice for every time that either of the other two is so moved.

13. A machine of the class described having, in combination, a bed for supporting a

piece of stock, a punch bar, means for reciprocating said bar, three or more punches carried by said bar and arranged to be operated one at a time, each punch being movable with respect to said bar into and out of operative position, and automatic means for causing one of said punches to be moved into said position oftener than another.

14. A machine of the class described having, in combination, a punch bar, a holder fast thereto, said holder being provided with a cylindrical socket the axis of which is at right angles to that of said punch bar, a turret loosely mounted in said socket, punches carried by said turret, means for removably holding said turret in place whereby said turret may readily be removed and replaced, means for operating said punch bar, automatic means for moving said turret angularly, and a stripper for coöperating with said punches.

In testimony whereof I have signed my name to this specification in the presence of two subscribing witnesses.

EDWARD A. STIGGINS.
